(57) **CLAIM**

The ornamental design for a bottle nozzle, as shown and described.

DESCRIPTION

FIG. 1 is a front perspective view of a bottle nozzle in accordance with our new design;

FIG. 2 is a front elevational view thereof;

FIG. 3 is a rear elevational view thereof;

FIG. 4 is a left side elevational view thereof;

FIG. 5 is a right side elevational view thereof; and,

FIG. 6 is a top plan view thereof.

The broken lines in the figures are for illustrative purposes only and form no part of the claimed design.

The bottom view of the bottle nozzle is not shown in the drawings or described in the specification and, therefore, forms no part of the claimed design.
